CARTON

Bruce J. Davidson, Kew Gardens, N. Y., assignor
to National Biscuit Company, New York, N. Y.,
a corporation of New Jersey

Application December 30, 1931, Serial No. 583,855

26 Claims. (Cl. 229—51)

My present invention relates to cartons such as are commonly used for packaging many kinds of merchandise, for example, bakery products, cereals, confections, soap powders, drug supplies, 5 cigarettes, and many other articles that are put up in sealed packages by the manufacturer and are sold to the ultimate consumer in their original containers.

Heretofore it has been the usual practice to seal 10 the cartons tightly at the factory, and they could be opened by the consumer only by tearing away a part of the package. In many instances the consumer does not use the entire contents of the package at once, and, if the package has been 15 torn, it cannot be reclosed satisfactorily. Therefore, one of the objects of my present invention is to produce a carton that can be sealed tightly by the manufacturer when it is filled, and yet be constructed so that it can be opened by the consumer without destroying the carton, and can be 20 reclosed easily and securely until some of its contents are wanted again.

Another object is to produce a carton that can be glued or otherwise securely sealed at the factory, and yet can be opened and reclosed repeatedly without breaking any part of the original glued closure and without the use of adhesives in reclosing.

Another object of the invention is to produce a 30 carton that is closed by fastening its several sides, ends and flaps together as has been commonly done by gluing heretofore, but having provision for opening the carton by severing along one or more weakened lines and having a tuck or tongue 35 that is adapted to be inserted within the carton to close it along the severed line when the carton is reclosed.

Another object of my invention is to produce a 40 carton of the kind referred to wherein all of the outer panels, ends and sides terminate at the respective edges of the box, so that the outside of the box is smooth or has no interrupted surfaces, and therefore may be satisfactorily enclosed 45 in an outer wrapper if desired.

The above and other objects and advantages will be understood by those skilled in the art, reference being now made to the accompanying drawings wherein I have illustrated some practicable embodiments of my invention and wherein—

Fig. 1 shows the blank from which one form of carton embodying my invention may be formed,

Fig. 2 shows the carton sealed at the side and 55 folded flat as it is made at the carton factory

ready to be shipped to the manufacturer to be filled and sealed at the ends,

Fig. 3 shows the carton after it has been opened by the consumer and also shows the tuck that is adapted to close the carton along the severed 5 line,

Fig. 4 shows a blank from which another carton embodying my invention may be formed,

Fig. 5 shows the carton sealed at the side and 10 folded flat for shipment,

Fig. 6 shows the carton filled and illustrates the manner of sealing the ends,

Fig. 7 shows one end of the sealed carton,

Fig. 8 shows the carton after it has been opened, 15 Figs. 9, 10 and 11 are similar views of a further embodiment of my invention.

The carton shown in Figs. 1, 2, and 3 is formed from a blank having score lines 12, 13, 14, 15, 16, and 17, and slits or cuts 18, 19, 20, and 21, which define a front panel 22, a bottom panel 23, a rear panel 24, a top panel 25, and tuck 26, extending in succession from one end to the other of the blank. The score lines 16 and 17, and the cuts 18 to 21 define flaps 27, 28, 29, and 30 at the ends of the front and rear panels 22, and 24, and at 25 the ends of the bottom panel 23 provide the two end panels 31 and 32, the width of these two end panels being equal to the width of the finished carton, and their length equal to the height of the box.

The material of the blank extends beyond these two end panels to provide flaps 33, and 34, which may be bent inwardly when the box is formed along the score lines 35, 36. The front panel 22 is also provided with a weakened, or tear line 37, 35 the ends of which terminate substantially at the upper corners of the front panel and which bends inwardly so that it is normally a sufficient distance inward from the edge of the front panel to provide a strip 38, that may be glued or otherwise secured to the tuck 26 when the box is assembled, the tuck 26 being wider than this glue strip.

After the blank has been cut out, scored and creased, as indicated in Fig. 1, it is folded along the score lines 13 and 15, with the tuck 26 lying under the panel 22, and the strip 38 is glued to the top edge of the tuck, as clearly shown in Fig. 2. The box is then flat and is shipped in this condition to the manufacturer, who, upon receiving it, fills it through the end, the flaps 27, 28, 29, and 30 preferably being turned inside of the end panels 31, 32, which are glued to the end flaps to secure the blank in box forming position. This style of carton is adapted to be filled through the 55

end, the manufacturer first straightening the carton of Fig. 2 into box form and then filling it through the end before the end flaps and end panels are secured in position.

- 5 When the box is filled and sealed, the flaps 33, 34 extend inwardly under the cover 25 and the tuck 26 lies inside of the front panel 22. When the consumer desires to open the package, he uses his thumb nail, or a blunt instrument, to 10 break the package along the tear line 37, which is just below the glued surface of the front panel at the top of the tuck 26. This enables the purchaser to raise the top, as shown in Fig. 3, to open the box, and when it is desired to reclose it after 15 using part of its contents, the tuck 26 is again inserted inside of the front panel 22, which successfully closes the box. If desired, the flaps 33, 34 may be very lightly glued to the top 25 so that they will readily break loose when the top is lifted.
- 20 In practice it has sometimes been found desirable to have the tuck 26 on the outside of the box and overlapping the tear line 37. When this is done, the front panel has a short glue flap that is glued to the underside of the cover. To open 25 the box, the tuck is raised to disclose the tear line 37, which is then broken, and the box opened by raising the tuck and cover. To reclose the box, the tuck is inserted inside of the front panel.

The form of carton box in Figs. 4 to 8 is formed 30 from the blank of Fig. 4, wherein the front panel 39, a bottom panel 40, a rear panel 41, a top 42, and a tuck 43 are formed in succession, being separated by score lines on which the blank is folded to form the box.

35 The front panel 39 has flaps 44, 45 formed at each end, these flaps being substantially the full size of the end of the box. A weakened or tear line 46 extends across the front panel and the two end flaps, terminating near the upper corners 40 of the flaps, and its distance from the edge of the front panel being sufficient to provide a glue strip 47. The bottom panel 40 has a flap 48, 49 at each end and the rear panel 41 has an end panel 50, 51 at each end, these end panels preferably being of the same size as the end of the finished carton. The top 42 has two end flaps 52, 53, to which the flaps 44 and 45 are secured when the box is completed.

Fig. 5 shows the carton as it is partly assembled 50 at the carton factory for shipment to the manufacturer. This carton is adapted to be filled from the end, and Fig. 6 shows the carton after it has been filled and is in process of being sealed. It will be noted that the tuck 43 lies inside of the 55 front panel 39, and that the end panels 50, 51 are inside of the other flaps. The flaps 48, 49, 52, and 53 lie next to the ends 50, 51, but are not glued thereto. The last operation in sealing the carton consists in applying an adhesive to the 60 flaps 44, 45, which are then turned in and adhere to the respective end panels and flaps on the top and bottom panels.

Fig. 7 shows one end of the box after it has been filled and sealed.

65 It will be noted that the tear line 46 on the end flaps 44, 45 coincides with the lower edges of the flaps 52, 53 on the cover, and that the tear line on the front panel 39 extends across the front of the box just below where it is glued to the upper 70 part of the tuck 43. I have shown this tuck 43 as being of greater width than the glue strip 47, but this is for purpose of illustration only, and in many instances this form of my invention will 75 have the width of the tuck equal to or less than

the width of the glue strip 47. When it is desired to open the box, the consumer will break it along the tear line 46, which releases the top and permits it to be opened as shown in Fig. 8. The carton obviously can be opened and reclosed as many times as the purchaser may find it necessary.

The blank of Fig. 9 has a front panel 54, bottom panel 55, rear panel 56, top 57, and tuck 58 defined thereon by score lines, and at the sides 10 has the flaps 59, 60, 61, and 62, and the end panels 63, 64, 65, and 66. The end panels and flaps 60 to 64 are defined by the score lines 67, 68, and the end panels 65, 66 by the tear lines 69, 70. The front panel 54 has a tear line 71, which is spaced 15 from its edge a sufficient distance to provide a glue strip 72 which, when the carton is formed, is secured to the tuck 58. It will be noted that the flaps 59 to 62 are cut away slightly at their top and bottom edges so that their height is slightly 20 less than the height of the finished carton. Fig. 10 shows the carton folded flat with the strip 72 glued to the tuck 58, the tuck lying inside of the front panel 54. The manufacturer receives the carton knocked down, as shown in Fig. 10, and to 25 fill it, opens it into box form and inserts its contents through the opened end. After the carton has been filled and is to be closed, the end panels 63, 64 are turned in and then the panels 65, 66 fixed over them. The adhesive is applied 30 to the four flaps 59, 60, 61 and 62, which are then turned in and not only glued together, but the inner one glued to the adjacent end 65 or 66, as the case may be. When the carton is filled and closed, the tear strips 69, 70 will be at the top of 35 the box, and the cut-away portions of the flaps 59 to 62 will permit access to these weakened lines. To open the box, the consumer breaks it along the lines 69, 70, and 71 with his finger nail, or any other suitable instrument, after which the 40 cover can be raised as illustrated in Fig. 11.

It will be noted in Figs. 1 to 3 and 9 to 11 that the tear lines 37 and 71 do not extend the full length of the box, and that their ends bend upwardly to the edge of the panel on which they are located and terminate substantially at or a short distance from the upper corners of the box so as to provide lips as indicated at 37' in Figs. 1 and 3 and at 71' in Figs. 9 to 11. The lips 37', 71' bind upon the flaps 26, 58, when the box 50 is reclosed, and hold the flaps in place. This is true because the cartons are made with the panels 23, 25 alike in width, as are also the panels 55, 57, so that when the flaps are inserted within the 55 carton they exert some pressure on the respective front panels 22, 54. If the tear lines extended all the way across the front panels, then there would be no binding action on the flaps when the boxes were reclosed.

While I have shown and described three forms of carton in which my invention may be embodied, it is to be understood that these are but 60 illustrative of the invention and that the invention may be embodied in many other modifications, and is not to be limited except as defined in my claims.

What I claim as my invention and desire to 65 secure by Letters Patent is:

1. A carton having front, rear, top and bottom panels, end panels fixedly secured to the front, rear and bottom panels, the top being hingedly secured at one edge to the rear panel and at its front edge having a tuck extending the full length of the top and lying within the front panel, the front panel having a weakened line spaced from 70 75

its upper edge with its ends bent upwardly substantially to the upper corners of the front panel where there are thus provided a pair of lips, said weakened line overlying said tuck, that portion 5 of said front panel above said weakened line being fixedly secured to said tuck.

2. A carton having front, rear, top and bottom panels, end panels fixedly secured to the front, rear and bottom panels, the top being hingedly 10 secured at one edge to the rear panel and at its front edge having a tuck lying within the front panel and extending the full length thereof, the front panel having a weakened line spaced from its edge, extending substantially its full length 15 and overlapped by said tuck, said weakened line extending lengthwise of said front panel and its ends being bent toward and terminating substantially at the upper corners thereof to provide a pair of lips thereon, that portion of said front 20 panel above said weakened line being fixedly secured to said tuck.

3. A carton having front, rear, bottom and end panels fixedly secured in carton forming relation, said front panel having a glue strip at its upper 25 edge and a weakened line extending lengthwise of said panel below the glue strip, said end panels having flaps extending inwardly from their upper edges, a top hingedly secured at one edge to the rear panel and at its other edge having a tuck 30 lying within the front panel, said glue strip being secured to said tuck adjacent its upper edge, said weakened line at both ends being bent upwardly and terminating substantially at the upper corners of said front panel to provide a pair of lips 35 thereon.

4. A carton blank provided with score lines defining in succession front, bottom, rear and top panels and a tuck, end panels defined by score lines and extending outwardly from the ends of 40 the bottom panel, end flaps extending outwardly from the ends of the front and rear panels and adapted to be secured to the end panels, said front panel having a glue strip adjacent its free 45 edge and within its borders adapted to be secured to said tuck, said glue strip being defined on said front panel by a tear line extending the full length of the panel and both ends bent upwardly to terminate at the edge of the front panel and provide a pair of lips at the upper corners 50 thereof.

5. A carton having front, rear, bottom and end panels, flaps fixedly securing the several panels in box forming relation, a top panel hingedly secured at one edge to the rear panel and at its 55 opposite edge having a tuck lying within the front panel, a weakened strip on the front panel secured to said tuck, said top panel having end flaps secured in fixed relation to the end panels, there being tear lines extending across said end 60 flaps whereby said top panel may be separated therefrom.

6. A carton having front, rear, bottom and end panels, flaps fixedly securing the several panels in box forming relation, a top panel hingedly secured at one edge to the rear panel and at its 65 opposite edge having a tuck lying within the front panel and extending below a weakened line thereon, said front panel above said weakened line being fixedly secured to said tuck, said top panel 70 having end flaps secured in fixed relation to the end panels, there being tear lines extending across said end flaps whereby said top panel may be separated therefrom.

7. A carton having front, bottom, rear and end 75 panels, the end panels extending upwardly from

the ends of the bottom panel, end flaps secured to the ends of the front and rear panels and secured to the end panels, said end flaps being of less width than the height of the carton, a top secured at one edge to the top of the rear panel 5 and at its opposite edge having a tuck lying within the front panel, said top having two flaps secured in fixed relation to the end panels and end flaps, there being tear lines across said top flaps adjacent the top edge of the carton, said front 10 panel being secured to said tuck and having a weakened line below the said secured edge.

8. A carton blank having provided in succession thereon front, bottom, rear, and top panels and a tuck, the front panel at its free edge having 15 a tear strip of less width than said tuck, the front and rear panels having flaps at each end, the bottom panel having an end panel at each end, and the top panel having an end panel at each end, there being a tear line extending across 20 each top end panel.

9. A carton having front, rear, top, bottom, and end panels, the top being hingedly secured at one edge to the rear panel and at its front edge having a tuck extending the full length of the 25 top and lying within the front panel, the front panel having a weakened line spaced from its upper edge with its ends bent upwardly substantially to the upper corners of the front panel where there are thus provided a pair of lips, said 30 weakened line overlying said tuck, that portion of said front panel above said weakened line being fixedly secured to said tuck.

10. In a carton of the character described, top, front, bottom and rear walls, end flaps integrally 35 associated with each of said walls, weakened lines joining said top and the end flaps associated therewith, a potential folding tuck integrally associated with said top and separably affixed to said front wall.

11. In a carton of the character described, top, front, bottom and rear walls, end flaps integrally 45 associated with each of said walls, weakened lines joining said top and the end flaps associated therewith, a potential folding tuck integrally associated with said top and adhesively affixed over part of its surface only to a proximate side wall.

12. In a device of the character described, the combination comprising a movable section provided with a flap forming a potential tucking-in 50 flap and initially overlying and in part only affixed to a proximate wall, the underlying portion of said wall being set off by a weakened line, and tabs detachably connected to said movable section along edges thereof adjacent said tucking-in flap.

13. In a device of the character described, the combination comprising a movable section provided with a flap forming a potential tucking-in 55 flap and initially overlying and in part only affixed to a proximate wall, the underlying portion of said wall being set off by a weakened line, and tabs connected to said movable section and separable therefrom along weakened lines extending along edges of the device and toward ends of said 60 first-mentioned weakened line.

14. A blank for a carton having potential folding tabs, a potential cover section provided with an extension forming a potential closing flap and provided with weakened lines extending from 70 the ends of said flap and setting off the folding tabs associated with said cover section, and a portion of the section which is to be overlain by said flap being set off by a score line.

15. In a carton provided with side walls, a top 75

- and bottom wall, each provided with an extension tab, a potential folding tuck connected with said top wall and initially overlying at least a part of an adjacent side wall of said carton and 5 being in part intersecured therewith, and weakened fold lines between said top and its associated tabs and along the edges of said carton, said underlying intersecured portion being set off from the remainder of said side wall by a score line.
- 10 16. A reclosable carton having a front wall with a transverse weakened line near its top, the top panel of the carton being connected along one edge to the rear wall of the carton, and at its other edge having a tongue secured to said front 10 wall and extending below said weakened line.
- 15 17. A carton having top, front, back and side walls, said top wall being provided with integral end tabs and with an integral potential folding tuck adapted to overlie a proximate side wall of 20 the carton, said folding tuck being adhesively affixed to said proximate side wall over a portion of their contiguous surfaces only, and said end tabs being joined to said top section along weakened lines.
- 25 18. A sealed carton comprising front, bottom, back, end and cover sections secured together so as to seal substantially the entire carton including all edges thereof, the cover having a tuck-in 30 flap on one edge thereof, and being hingedly secured at its opposite edge to the adjacent section of the carton, said cover being integral with portions which form at least the entire outer layer of said end sections, said portions being adapted to be severed from said cover along a weakened 35 line positioned substantially along the edge of said carton.
19. A carton having front, bottom, back and top sections, said top section being a hinged integral extension of said back section, flaps integral 40 with three sides of said top section and adapted to secure said top section to each of said front and side sections, and means adapted to facilitate the severance of a plurality of said flaps entirely from said top section along the top edge of said carton 45 whereby said top section is without extensions, where said plurality have been removed.
- 50 20. A carton having front, bottom, back, side and top sections, said top section being a hinged integral extension of said back section, flaps integral 55 with three sides of said top section and adapted to secure said top section to each of said front and side sections, and means comprising scored lines adapted to facilitate the severance of said top section from each of said front and side sections, the score lines associated with the severance from the side sections being along the top edges whereby said top section, when it is raised, is without extensions along the sides.
- 55 21. A sealed carton comprising integral front, bottom, back and cover sections, end sections inte- gral with the front, bottom and back sections and folded together and sealed by means of an adhesive, said cover section having an integral tuck-in flap and integral sealing portions, said flap and portions lying inside the front and end sections 5 of said carton respectively, said flap and portions being adapted to seal the cover section to the end sections and to the front section, said sealing portions being readily severable from said cover section along weakened lines, and said tuck-in flap 10 being readily severable from said front section along a weakened line whereby the carton may be opened by breaking along said weakened lines and the cover and its depending tuck-in flap raised.
22. A carton having front, bottom, back, side and top sections, said top section being a hinged integral extension of said back section, flaps integral 20 with three sides of each top section and adapted to secure said top section to each of said front and side sections, and means comprising scored lines adapted to facilitate the severance of said top section from each of said front and side sections.
23. A carton having front, bottom, rear and end 25 walls, a top section hinged at one side to the top of said rear wall, said top section having an extension lying within said walls and secured thereto, the part secured to said extension being defined by a weakened line having upturned ends 30 extending substantially to the corners of the carton.
24. A carton having four side and two end walls, the top wall having a downwardly turned tuck at 35 each end, the front wall being secured near its top edge to said tuck and at each end having a flap secured to the end of the box and to said top wall flaps, said front wall and its flaps having a tear line adjacent the portions secured to said 40 tuck and top wall flaps.
25. A carton having front, bottom, rear, top and end panels, flaps on said top panel overlapping said end panels and a tuck lying within said front panel, flaps on said front panel secured to 45 said end panels and to said top flaps, the front panel being secured to said tuck, there being a tear line on said front panel below the part secured to said tuck, and tear lines on said front flaps adjacent the lower edges of said top flaps. 50
26. A carton forming blank having formed in succession thereon front, bottom, rear and top panels and a tuck, end panels provided at the ends of the rear panel, short end flaps at the ends of the top and bottom panels, said front panel 55 having end flaps adapted to be secured to said end panels and aforesaid end flaps, there being a tear line extending across said front panel and its end flaps.

BRUCE J. DAVIDSON. 60
